GRATING FOR DECKS OR THE LIKE

Ernest C. Liskey, Jr., Severna Park, Md.

Application March 31, 1952, Serial No. 19,125

Term of patent 14 years

(CL. D13—1)

To all whom it may concern:

Be it known that I, Ernest C. Liskey, Jr., a citizen of the United States, residing at Severna Park, in the county of Anne Arundel, State of Maryland, have invented a new, original, and ornamental Design for a Grating for Decks or the like, of which the following is a specification, reference being had to the accompanying drawing, forming part thereof.

In the drawing:

Figure 1 is a perspective view of a grating for decks or the like showing my new design; and Figure 2 is an end elevation thereof.

I claim:

The ornamental design for a grating for decks or the like, as shown.

ERNEST C. LISKEY, JR.
